UNITED STATES PATENT OFFICE.

ROBERT V. BINGAY, OF PITTSBURGH, PENNSYLVANIA, ASSIGNOR TO PITTSBURGH
TRANSFORMER COMPANY, A CORPORATION OF PENNSYLVANIA.

TRANSFORMER CONSTRUCTION.

1,425,504.

Specification of Letters Patent. Patented Aug. 15, 1922.

Application filed October 17, 1919. Serial No. 331,324.

To all whom it may concern:

Be it known that I, ROBERT V. BINGAY, a citizen of the United States, residing at Pittsburgh, in the county of Allegheny and State of Pennsylvania, have invented certain new and useful Improvements in Transformer Constructions, of which the following is a specification.

This invention relates to electrical transformers and particularly to the mechanical construction of the supporting parts of a transformer casing. The object of the invention is to provide a transformer structure which will be strong and at the same time inexpensive in its cost of production.

In prior structures the transformer casing has had a top and supporting base of metal constructed or cast to fit and sustain the parts. Such metal construction when of sufficient size and strength is cumbersome and costly, requiring a very heavy top to have sufficient strength to prevent buckling when lifted, and a very large base.

In the transformer of this invention the objections to these prior structures is overcome and the transformer casing is provided with a top and base of strong and durable construction at a great reduction in cost.

30 In the accompanying drawings

Fig. 1 is a view in elevation with parts broken away and in section of a transformer illustrating one embodiment of this invention, and

35 Fig. 2 is a view in vertical section of a detail of Fig. 1.

In the embodiment of the invention shown in the drawings a tank 3 containing the transformer core and coils immersed in oil is supported on a base 4 and has a top or cover 5. Vertical tie rods 16 connect the cover to the coil supporting frames and vertical tie rods 7 fasten the cover and with it the tank to the base 4. The transformer in assembled condition is lifted by means of these outer tie rods 7.

The base 4 is of reinforced concrete construction comprising edge I-beams 10 or other suitable metal edge within which is formed the concrete slab 11 having longitudinal reinforcing members 12 and transverse reinforcing members 13. The top sur-

face of the base is provided with transverse channel bars 14 having their upper flat surfaces raised above the surface of the concrete and adapted to support the tank 3 away from the base so that the bottom of the tank will not be corroded by moisture. Anchorages for the rods 7 are provided by metal strips 20 imbedded in the under surface of the concrete and bent as at 21 to form pockets for the lower ends of rods 7 and their nuts 17.

The top 5 of the transformer tank is composed of reinforced concrete having a top plate 6, opening 25 and cover 26. In the formation of this top the plate 6 may be turned upside down and the manhole aperture 25 and other apertures provided with filling blocks or frames to exclude the concrete, which is then poured upon the plate covering the reinforcing rods 28 and leveled off to any desired thicknesses. When set, this concrete filler forms a slab of great strength resisting compression and supporting the top against flexure when the transformer is lifted.

The reinforced concrete construction of this invention adds to the strength of the transformer parts and at the same time greatly reduces the cost of production. Hitherto special patterns were required for the bases of each size and type of transformer; the concrete bases of this invention can be readily built up for each different transformer at a small fraction of the cost of the prior castings or steel structures.

I claim:

1. The combination with a sheet metal tank having a cover, of a supporting base for said tank comprising a metal frame set with a slab of reinforced concrete, and clamping rods extending between said base and cover to clamp said tank on said base. 90

2. The combination with a sheet metal tank having a cover, of a supporting base for said tank comprising a metal frame of channel bars with inward directed flanges within in which is set a slab of reinforced concrete, and clamping rods extending between said base and cover to clamp said tank on said base. 100

3. The combination with a transformer

tank having a bottom, of a supporting base therefor comprising a reinforced concrete slab having metal surface ribs for supporting said tank bottom at separated points, 5 lifting rods attached to said base, and strips in said concrete serving as anchorages for said rods.

4. The combination with a transformer tank having a bottom, of a supporting base therefor comprising a reinforced concrete slab, metal strips on the surface of said slab forming ribs for supporting said tank, and lifting rods attached to said base. 10

ROBERT V. BINGAY.
